PRUNING SHEAR

Joseph J. F. March, 82 Windsor St., Waterbury, Conn.

Filed Dec. 3, 1962, Ser. No. 72,703

Term of patent 14 years

(Cl. D22—4)

FIG. 1

FIG. 2

FIG. 3

FIG. 4

FIG. 5

FIG. 1 is a perspective view of a pruning shear embodying my new design showing one side thereof;

FIG. 2 is a side elevational view thereof on an enlarged scale showing the opposite side of the pruning shear;

FIG. 3 is a bottom plan view of the pruning shear of FIG. 2;

FIG. 4 is a right-end elevational view of the pruning shear of FIG. 2; and

FIG. 5 is a side elevational view on a reduced scale showing the side of the pruning shear illustrated in FIG. 2 with the blades in open position.

The dominant features of my design reside in the portions shown in full lines, and a characteristic feature of the design is the rib structure positioned as shown in the drawing.

I claim:

The ornamental design for a pruning shear, as shown and described.
